CLAIM

The ornamental design for a tensioning connector element for furniture pieces or the like, as shown.

DESCRIPTION

FIG. 1 is a horizontal view of a tensioning connector element according to the invention,
FIG. 2 is a perspective view of the tensioning connector element, on an enlarged scale, and
FIG. 3 is another perspective view of the tensioning connector element, also on an enlarged scale.

FIG. 1

FIG. 2

FIG. 3
